UNITED STATES PATENT OFFICE.

ALBERT P. SEYMOUR, OF SYRACUSE, NEW YORK.

INSULATOR.

SPECIFICATION forming part of Letters Patent No. 483,771, dated October 4, 1892.

Application filed March 5, 1892. Serial No. 423,830. (No model.)

To all whom it may concern:

Be it known that I, ALBERT P. SEYMOUR, a citizen of the United States, and a resident of Syracuse, in the county of Onondaga and 5 State of New York, have invented a certain new and useful Wiring-Insulator, of which the following is a specification.

My invention relates to the construction of electric wiring-insulators, and more particularly to porcelain-block insulators adapted to be secured to ceilings, walls, or other plane surfaces.

The object of my invention is to provide a porcelain-block insulator that may be held or 15 fastened by a single central screw, and that shall at the same time hold the wire securely without tie-wires and without making a loop or turn in the wire itself and which shall, moreover, not be liable to turn by the tension 20 of the wire.

The invention consists in the new article of manufacture hereinafter described and comprising, essentially, a solid block of porcelain provided on its periphery at one end with two 25 hooks or lugs disposed on opposite sides of the line in which the wire lies when passed beneath both the lugs or hooks and having a central axial perforation extending through it endwise from the central depressed or re- 30 cesses portion between the lugs or hooks where the wire lies.

My invention consists, further, in other features of construction hereinafter described, and more particularly specified in the claims.

35 In the accompanying drawings, Figure 1 is a perspective view of an insulator embodying my invention, a piece of wire being shown in place therein. Fig. 2 is a vertical central section of the insulator on a line parallel to 40 the wire held therein.

A indicates a solid block of porcelain or similar good insulating substance, and B the hooks or lugs which, as shown in the perspective, lie at opposite sides of the line-wire 45 L and project from the body of the block at the end opposite that which rests upon the surface of the wall or ceiling. Grooves C exist at the side of the insulator, which are for the purpose of facilitating the formation 50 of the plastic body of clay by a die or in a press.

At D are openings forming a space to allow the wire to be passed under the hook.

E is a central axial perforation extending endwise through the block from the central 55 depressed or recessed portion between the lugs or hooks where the wire L lies. This perforation receives the screw which fastens the insulator-block to a suitable support, the end of said insulator opposite the hooks B 60 resting upon the surface of such support. At the end bearing upon the surface of the support the block is furnished with several feet or studs G, which studs are preferably rounded or pointed at their ends, so that there is but 65 little surface contact between the insulator and the body to which it is secured.

As will be seen from the vertical section, the inside or under side of the hooks or lugs upon which the wire bears is nearly on a level with 70 the surface of the central depressed portion around the perforation, at which part the wire also is supported, the effect being to produce a bend in the wire at this point which holds the wire fast.

75 As will be observed, the wire runs through the center of the insulator, and any tension on it will not have the effect of turning the insulator, and thus throwing slack onto the wire on one side. The central perforation is 80 countersunk at its outer end, as shown, so that the head of the screw will be well below the wire, and a short screw may be employed for fastening the insulator to a ceiling. It will be observed, further, that the end of the 85 perforation for the screw is guarded by the wire, so that the screw cannot fall out of the insulator. The central depressed portion upon which the wire rests between the hooks forms, in effect, a shoulder adapted to bend the 90 wire in a direction transverse to the direction in which the wire has to be bent or deflected in order to enter it under the second hook. After the insulator is fastened in position the wire is simply applied by fastening 95 it under one lug, pulling it tight, and then deflecting it to one side and passing it under the other lug, the slight bend which is necessary to thus pass it under the other lug serving to hold it fast.

100 As will be observed, the insulator is not only securely fastened, but the wire is held a good

distance from the ceiling or other support which is not the case in any of the block insulators at present in use for electric wiring purposes.

5. What I claim as my invention is—

1. As a new article of manufacture, a block insulator consisting of a solid block or piece of porcelain or similar material provided on its periphery at one end with two hooks or lugs disposed on opposite sides of the line in which the wire lies when passed beneath both said lugs or hooks and having a central axial perforation extending through the block end-wise from a depressed or recessed end portion lying between the lugs or hooks, as and for the purpose described.
2. As a new article of manufacture, a block insulator provided at the end that engages the surface of the support with a number of bearing-studs projecting directly from the body thereof at a number of points between the edge and the central perforation for the fastening-screw.
3. As a new article of manufacture, a block insulator consisting of a solid block of porcelain, having at one end two hooks or lugs in-

closing a central depressed end portion from which extends a hole centrally through the block to the opposite end, where the block is provided with several bearing studs or projections engaging the surface to which it is applied. 30

4. As a new article of manufacture, a wiring-insulator consisting of a solid block of porcelain or similar material, having at one end a pair of hooks lying on opposite sides of the line in which the wire lies, a central depressed or recessed portion at the same end connected with the opposite end of the block by a countersunk hole or perforation, said depressed portion and hooks being disposed or arranged so as to tend to produce a slight bend in the wire in a direction transverse to that in which it has to be bent or deflected in order to pass it under the hooks or lugs. 45

Signed at Syracuse, in the county of Onondaga and State of New York, this 2d day of March, A. D. 1892.

ALBERT P. SEYMOUR.
